UNITED STATES PATENT OFFICE.

JOHN L. FAULHABER, OF FOSTORIA, OHIO.

DESIGN FOR A ROOFING-PLATE.

SPECIFICATION forming part of Design No. 21,313, dated January 26, 1892.

Application filed October 26, 1891. Serial No. 409,928. Term of patent 14 years.

To all whom it may concern:

Be it known that I, JOHN L. FAULHABER, a citizen of the United States, residing at Fostoria, in the county of Seneca and State of Ohio, have invented a new and original Design for Roofing-Sheets, of which the following is a specification.

The invention relates to a new and original design for a roofing-plate.

10 The object of the present invention is to provide a roofing-plate which will present an ornamental and attractive appearance.

15 The essential feature of the invention resides in the particular shape of the roofing-plate; and it consists of V-shaped crimps and convexly and concavely curved portions arranged between the crimps.

20 In the drawings, Figure 1 is a perspective view of a portion of a roofing-plate. Fig. 2 is a sectional view of the same.

Like numerals of reference indicate like parts in all the figures of the drawings.

1 designates a portion of a roofing-plate provided at opposite sides with V-shaped crimps

or bends 2 and having arranged between the 25 V-shaped crimps convexly and concavely curved portions 3 and 4. The convex portions are arranged adjacent to the V-shaped crimps and are separated from them by slightly-depressed portions 5. The concaved portion 4 30 is arranged between the convex portions 3, and it forms with them a continuous sigmoidally-curved portion between the V-shaped crimps.

What I claim is—

35 The design for a roofing-plate, as herein shown, the same consisting of a plate provided at its longitudinal edges with V-shaped crimps and having arranged between the crimps the convexly and concavely curved portions, as 40 set forth.

In testimony that I claim the foregoing as my own I have hereto affixed my signature in the presence of two witnesses.

JOHN L. FAULHABER.
